UNITED STATES PATENT OFFICE.

CLYDE N. FRIZ, OF BALTIMORE, MARYLAND.

METHOD OF COMPACTING EARTH.

Application filed January 27, 1927. Serial No. 164,088.

The invention relates to the compaction of earth in preparation for placing structures such as buildings, roads, railways, or the like, thereon and has as an object the provision 5 of a method whereby the earth may be compacted to a considerable depth and to substantially the consistence of rotten rock.

It is a further object of the invention to 10 form the excavation for buildings and for the footings thereof in whole or in part by the compaction of the earth below the site without removal of all of the earth from such excavation.

It is a further object of the invention to 15 compact earth as referred to and to place sheet piling around the margins of an excavation while placing the form into which the earth is to be compacted.

It is a further object of the invention to 20 provide apparatus for carrying out the method.

Further objects of the invention will appear from the following description when read in connection with the accompanying 25 drawings showing an illustrative embodiment of the invention and wherein:

Fig. 1 is a plan view showing certain forms in situ and indicating portions of earth already compacted;

Fig. 2 is a vertical section of a guide for 30 a hammer for placing the forms, showing two forms in elevation;

Fig. 3 is a like view showing the driving head for the form removed and the hammer 35 in position for compacting the earth within one of the forms, the first form having been removed;

Fig. 4 is a transverse section of the guide shown in Figs. 2 and 3;

Fig. 5 is a plan view of the modified form 40 of compacting form showing the plurality thereof which may be left in situ during construction of a foundation to serve as sheet piling;

Fig. 6 is a side elevation of a type of form 45 for compaction showing plank sheet piling to be placed simultaneously with the driving of the form;

Fig. 7 is a vertical section on line 7—7 of 50 Fig. 8;

Fig. 8 is a detail plan view of a portion of 55 an excavation surrounded with the sheet pilings of Fig. 7;

Fig. 9 is a plan view of the structure of 55 Fig. 6; and

Fig. 10 is a vertical section of a marine device.

In the compaction of earth as heretofore provided either by a roller or by a hammer, the weight of the compacting instrument is 60 borne by a pyramid of earth in which the earth is most greatly condensed at the surface and in which the density lessens as the supporting pyramid widens below the surface. The side of the pyramid is to some extent 65

similar to the angle of repose of the material under compaction as modified by the surrounding uncompacted earth. Because of this fact, by heretofore known methods, it has only been possible to compact the earth 70 to any great extent for a slight distance below the surface, at least without the use of compacting weights in excess of that which it is practicable to apply. According to the present process, a column of earth to be compacted is segregated from the surrounding earth and must therefore support the weight 75 and impact of the compacting instrument solely upon the cross section of the column,

by virtue of which method the earth may be compacted to a considerable depth through the segregated area. 80

By virtue of the present process, it is possible to make a fill for a railway or the like, and, by carrying out the process through the fill, to compact the entire fill to such a density that no settlement will occur and the railway or roadway or a building may immediately be placed upon the fill without further settlement. In the erection of buildings, unless piles have been carried to bed rock, there has always been a settlement of the building and it has been the hope of the builder, which is not always well founded, that the settlement will take place evenly to leave the 90 building plumb after settlement has ceased. A building placed upon a site according to the present invention will settle little if any and therefore the danger of its going out of plumb is removed. 100

As shown in Figure 1, the portions 10, 11, 12, 13, 14, and 15 show areas of previous compaction. For the purposes of the invention a form preferably of steel, two of which are indicated at 16, and 17, is utilized. In 105 the first compacted portion, as 10, the form

16 is shown in dotted lines and the compaction is started at one side of the portion to be treated, the result of the initial treatment being to compact a portion of earth which is 5 vertical against the two sides of form 16 and the compaction opposite the open sides of the form will be the surface of a pyramid as above referred to in the old practice. The sloping portion of the compaction will also 10 be present through the portions 11 to 15 inclusive but the sides of these compacted portions abutting against the previously compacted portion will be vertical since the action of the impacting instrument will be 15 confined upon three sides throughout these portions, two of the sides being segregated by the form 16 or 17 and a third side being confined by the previously compacted column. In the position of the form shown at 20 17, as well as throughout the interior of the area to be compacted, each compacted column of earth will be confined upon four sides. The confinement upon two sides of each column will result from the use of form 25 16 or 17 and the remaining two sides will be confined by the sides of the previously compacted columns. In this manner a railway or roadway fill may be compacted through the enclosed area to a considerable depth as 30 already referred to and will be bounded by a lesser compacted area, the sides of which slope outwardly and downwardly.

As shown in Figure 2, the lower edge of one side of each form is cut upon a diagonal 35 as indicated at 18, 19, to cause the form to hug the previous form in a manner well understood in the driving of sheet piling. To prevent battering or brooming of the upper edge of the form under the impact of 40 the hammer 20, a driving head 21 is indicated as resting upon the upper end of the form. To guide the hammer in its blows, there is provided a hollow shell 22, shown as integral with the form 16 or 17 provided 45 with a slot to receive the driving head 21 and from which the head may be removed when the form has been placed, allowing the blows of the hammer to fall upon the earth within the form, guided so as to strike accurately upon the column of earth 50 under treatment by means of shell 22. If it be desired to protect the columns already compacted from disturbance during compacting of succeeding portions, a form of the character shown in Figure 5 at 26 may be utilized which form comprises a three sided structure open upon the remaining side. A row of such forms are shown in Figure 5 55 which may be left in place to prevent the disturbance referred to through subsequent operations. In this figure, previously compacted areas are indicated at 27.

If it be desired to place sheet piling about an excavation as indicated in Figures 7, 8, 60 and 9, a form is provided having a driving

head 28 seating upon the form and having a depending flange 29. Sheet piling such as two-inch planks 23 may be placed against the side of the form as indicated in Figure 9, which planks will lie in contact with the 65 side of the form and will be overlapped by the head 28, the flange 29 holding the planks at their upper edge closely against the surface of the form. The form and planks may therefore be driven simultaneously, the earth 70 compacted within the form, and the earth may then be removed leaving the planks in place to serve as sheet piling. By this method, the planks will not deteriorate in 75 service and may be salvaged in substantially 80 their former condition for reuse.

In Figure 7, the planks are indicated as bevelled at their lower ends 30 to cause the planks to hug the form while being driven. To brace the thus provided sheet piling 85 wales 24 may be placed against the planks and braces 38 resting against stakes 38' driven in the compacted area, may be provided to support the piling.

In the formation of excavations, the amount of compaction possible or desirable 90 may be estimated and a portion of the soil indicated at 31 may be removed after which the portion indicated at 32 may be compacted to provide the desired depth of excavation. The amount which it is necessary to thus remove will, as stated, vary with the character of the soil and in the case of the new fills, the entire excavation may be provided without removal of any of the soil 95 upon the site thus avoiding the necessity of steam shovel work and of hauling away material which it is desirable to retain below the site in compacted form. For purposes of excavation, the site may be uniformly compacted throughout after which 100 portions for the outside wall, which portions are indicated at 33, 34, may be still further compacted to provide a footing trench. Further portions within the excavation indicated at 35, 36, 37, etc. may again be 105 segregated and these portions further compacted to provide depressed areas of maximum compaction for reception of the column 110 footing throughout the site.

Waterways may be deepened by the process of the invention instead of by dredging, and for this purpose the device of Fig. 10 is provided. In this figure, a closed form and guide 39 are shown having a diaphragm 40 provided with a packing 41 to exclude water. Such form is placed against the bottom of the waterway with the diaphragm 40 lying thereagainst when the form is driven by the hammer falling on the driving head 42, with upward displacement of the diaphragm in the form. The head is then removed and the strata compacted by blows of the hammer upon the diaphragm.

Varying characters of column segregating 115

forms may be utilized and minor changes may be made in the steps of the process without departing from the spirit of the invention within the scope of the appended 5 claims.

I claim:

1. The process of compacting earth which comprises segregating and compacting in situ successive portions of the earth to provide a 10 maximum compaction over a considerable area.

2. The process of compacting earth which comprises segregating a portion of the earth and compacting the same in situ, segregating 15 successive portions of earth using a portion already compacted as one part of each successive segregating means and compacting each successive portion in turn.

3. The process of compacting earth which 20 comprises placing an open sided form successively about a boundary of area to be compacted and compacting the earth within the same, the outer boundary of the compacted material sloping downwardly and outwardly about said area, successively placing 25 said form within said boundary and compacting vertical sided columns of thus segregated portions to provide the maximum compaction to a considerable depth throughout the area to be compacted.

4. The process of simultaneously compacting earth and producing an excavation which 30 comprises segregating successive portions of the earth within the excavation area and condensing the earth in such successive portions whereby to lower the general level of the excavation to the desired depth and to provide a foundation through the excavation of the compacted earth.

40 5. The process of simultaneously compact-

ing earth and producing an excavation which comprises segregating successive portions of the earth within the excavation area and condensing the earth in such successive portions whereby to lower the general level of 45 the excavation to the desired depth and to provide a foundation through the excavation of the compacted earth and compacting footing areas within said excavation to reduce their level below the general level of the 50 excavation.

6. The process of simultaneously compacting earth and producing an excavation having a sheet piling supported boundary which comprises simultaneously driving a form and sheet piling about the boundary of said excavation, compacting the earth in successive portions of said boundary, removing the form and leaving the sheet piling in place, segregating successive portions of the 55 interior of the excavation site and compacting the successive portions in the order segregated whereby to lower the area of the excavation to the desired depth.

7. Means for compacting earth comprising 60 an open sided form, a polygonal guide having means coacting with the end of said form to guide the blows of a hammer utilized for compaction of the earth within the form.

8. A driving head for simultaneously inserting sheet piling and a hollow form within which to compact earth comprising a head having a socket to fit over the form and a ledge depending upon one side of the socket adapted to overlie the end of the sheet piling 75 in contact with the form and to hold the same thereagainst in the act of driving both the form and the sheet piling.
